B. RUBINSTEIN,

CLOTH CLAMP.

APPLICATION FILED JULY 16, 1921.

1,435,981.

Patented Nov. 21, 1922.

UNITED STATES PATENT OFFICE.

BARNETT RUBINSTEIN, OF ST. LOUIS, MISSOURI.

CLOTH CLAMP.

Application filed July 16, 1921. Serial No. 465,348.

To all whom it may concern:

Be it known that I, BARNETT RUBINSTEIN, a citizen of the United States, residing at the city of St. Louis, and State of Missouri, have invented a certain new and useful Improvement in Cloth Clamps, of which the following is a full, clear, and exact description, such as will enable others, skilled in the art to which it appertains, to make and use 10 the same, reference being had to the accompanying drawings, forming part of this application.

This invention relates to clamping devices for holding the fabric in position while it is 15 being cut or spread upon the table, and is an improvement upon the clamp for cloth cutting machines disclosed in Letters Patent of the United States No. 1,389,320, granted to me August 30, 1921.

20 The objects of the present invention are to provide a cloth clamping device which can be used at any point on the table intermediate its ends as well as at the ends of the table, and which device is detachable so 25 that it can be removed from the table when not in use, thereby leaving the surface thereof free from obstructions and projections.

Further objects of my invention are to 30 provide a device of the class described which can be effectively used in connection with a table of any width without distorting or affecting the efficient operation of the clamping bar and to provide actuating means for said clamping bar whereby the latter can be 35 moved upwardly a sufficient distance to clear the ends of the fabric and permit said ends to resume their normal positions on the table so that said bar upon its return movement will automatically engage and clamp the 40 ends of the fabric in position.

With the foregoing and other objects in view, my invention consists in certain novel features of construction and arrangements of parts hereinafter more fully described 45 and claimed, and illustrated in the accompanying drawings, in which—

Figure 1 is a plan view of one end of a cutting table showing the fabric clamp in position thereon.

50 Figure 2 is a plan view of an intermediate portion of a cutting table and showing the location of the clamping bar.

Figure 3 is a front elevation of the table shown in Figure 1.

Figure 4 is a longitudinal vertical cross section taken on line 4—4 of Figure 1.

Figure 5 is a fragmental vertical cross section of a table and the cloth positioned thereon and showing the position of the clamping bar before the same is actuated.

Figure 6 is a similar view of the bar in clamping position and showing in dotted lines said bar in its extreme upward position.

Figure 7 is a vertical cross section taken on line 7—7 of Figure 1.

Figure 8 is a vertical cross section taken longitudinally through the treadle and showing the adjustable connections between said treadle and the adjusting means.

Referring by numerals to the accompanying drawings, 10 designates a cutting table which is arranged to receive a cloth 11. This table is generally of a predetermined length to receive bolts of cloth when the same are spread thereon. In spreading the bolts, the 75 ends of the cloth are placed at the front or lefthand end of the table and are clamped in position so that the operator may properly arrange the cloth on the table.

The clamping means consist of a clamping bar 14, transversely disposed on top of the table and movable vertically by means of rods 15 which extend upwardly through the table and have their upper ends seated in the ends of bar 14. These ends 16 of rods 15 are threaded and are reduced in diameter so as to form shoulders 17 against which the ends of bar 14 are forced by means of nuts 18 which are screw-seated on the threaded ends 16. The vertically disposed openings 80 formed in table 10 for the passage of rods 15 are lined with tubular members 19 which form bearings for said rods and eliminate friction or binding action and maintain rods 15 in proper operative alignment. The lower 85 ends of these rods which extend downwardly below the table are threaded, as indicated at 20, and are seated in the ends of a transverse member 21 located a suitable distance below table 10. Nuts 22 are screwseated on the threaded ends 20 above and below each end of the transverse bar 21 so that the latter can be adjusted vertically with respect to rods 15 by moving nuts 22 up or down on the threaded ends 20.

100 Eye bolts 24 have threaded engagement with transverse member 21 adjacent to each rod 15 and are locked in position by lock-

105

nuts 25. These eye bolts are presented downwardly, and connected to each eye bolt is the upper end of a contraction spring 26, the lower end of which is anchored to the floor 5 by means of an eye bolt 27. Springs 26 are under tension and tend to hold the clamping bar 14 downwardly against table 10 so that when the fabric is placed therebetween, it will be firmly clamped in position. Springs 10 26 are of the proper length and have the required expansion to permit vertical movement of bar 14 upwardly a sufficient distance to clear the ends of the cloth 11. The tension of springs 26 can be regulated by releasing lock nuts 25 and adjusting eye bolts 24 vertically on transverse member 21.

Extending upwardly from member 21, and spaced equidistant from rods 15 are eye bolts 28 provided with lock nuts 29. Pivoted 20 connected to eye bolts 28 are the lower ends of vertically disposed links 30, to the upper ends of which are pivotally connected the outer or divergent ends of arms 31. Depending from the underside of table 10 are 25 bearings 32 provided with a vertically disposed series of apertures or seats 34, which are adapted to receive screws or pins 35, the latter forming pivotal supports for arms 31. Each arm 31 is provided with a longitudinally 30 disposed series of apertures 36 designed to receive a pin or screw 35. Thus by removing a pin 35, arms 31 can be adjusted longitudinally by bringing one of the other apertures 36 in alignment with aperture 34, 35 or vertically by transferring the pin 35 to another of said apertures 34.

The inner ends of arms 31 are connected to a treadle 37 by means of link 38 and chain 39, said chain forming a flexible connection 40 between the upper end of link 38 and pin 40 seated in the inner ends of arms 31. These inner ends are preferably joined together by a block 41 secured thereto in any suitable manner so as to reinforce and stiffen said 45 ends. If desired, arms 31 could be cast in one piece or formed by bending a bar to suitable shape. The lower end of link 38 is provided with an aperture in which is seated a hook 42, the lower end of which is threaded 50 and carries a nut 44.

The rear end of treadle 37 is pivotally mounted in bearing 45 extending upwardly from the floor. That portion of the treadle which is immediately below link 38 is provided 55 with a longitudinally disposed slot 46 and downwardly presented non-circular recesses 47. Slot 46 permits the passage of the shank of hook 42 therethrough so that the nut 44 carried by the lower end of hook 60 42 can enter and be seated in any one of recesses 47 thereby providing an easy adjustment of link 38 with respect to the pivotal support of treadle 37.

In cutting out lots of cloth for shirts, bolts 65 of cloth are spread upon the table in layers

which vary in thickness due to the number of bolts used and the nature of the cloth. In arranging the cloth on the table, the ends of the bolt are located at the left hand of the operator and clamped in position by means 70 of a bar 14, after which the cloth is spread out on the table. Heretofore, it has been necessary to manually operate the clamping means after each positioning of the ends of the cloth at the respective end of the table. 75 By use of my device, the ends of the cloth are placed on the table as shown in Figure 5, and treadle 37 is then operated to bring the clamping bar 14 into the position shown in dotted lines in Figures 3 and 6. The upward movement of bar 14 carries the ends of the cloth upwardly until they are clear of bar 14, whereupon they will fall back into their proper position on table 10. When pressure is removed from the treadle 37, bar 85 14 is released, and under the influence of springs 26, will move downwardly and engage the ends of the cloth.

The tables used in cutting-rooms are generally of a great length so as to accommodate a complete bolt of goods. When a small lot of shirts, or other garments, is desired, as in custom work, the different lots are arranged in short lengths upon the cutting table so that a number of operators can 95 be engaged at the same table in cutting these lots. By providing tubular members 19 at suitable intervals on the cutting table, clamping bars 14 can be moved to any position on the table by removing nuts 18 from the threaded ends of rods 15 so that the clamping bar 14 can be lifted and moved to the desired position, while rods 15 will move downwardly, thereby leaving the table free 100 from any projections.

A clamping device constructed in accordance with my invention is simple in operation and inexpensive to manufacture, and can be very easily removed from the table when not in use.

Obviously, various changes in the form and construction of my improved clamping device can be made and substituted for those herein shown and described without departing from my invention, and I do not wish 110 herein described.

What I claim is:

1. In a cloth clamping device, the combination of table, a clamping bar transversely mounted thereon and movable vertically with respect thereto, rods detachably secured to the ends of said bar and extending downwardly through said table, a transverse member adjustably connected to the lower 120 ends of said rods, contraction springs connected at their upper ends to said transverse member and having their lower ends anchored to the floor, a plurality of levers pivotally supported on the underside of said 125 table.

table, links connecting the free ends of said levers with said transverse member at points equidistant from the points of attachment of said rods and said transverse bar, and a treadle for operating said levers.

2. In a cloth clamping device, the combination of a table, open ended tubular members vertically disposed therein, rods mounted for vertical movement in said tubular members, a clamping bar detachably secured to the upper ends of said rods, a transverse member detachably carried by the lower ends of said rods, contraction springs having their lower ends anchored to the floor, and their upper ends adjustably fixed to said transverse member, whereby said clamping bar has a tendency to move towards said table, a plurality of upwardly presented members adjustably seated in said transverse member and in spaced relation with the points of connection between said rod and said transverse member, links pivotally connected to said upwardly extending members, bearings depending from the underside of said table, and foot-operated levers mounted in said bearings and pivotally connected to said links.

3. In a cloth clamping device, the combination of a table, rods mounted for vertical movement in said table, a clamping bar detachably secured to the upper ends of said rods, a transverse member adjustably carried by the lower ends of said rods, contraction springs having their lower ends anchored to the floor and their upper ends adjustably secured to said transverse member, a bearing fixed to the underside of said

table, a lever pivotally mounted in said bearing and having a plurality of pivotal connections with said transverse member, said lever being adjustable vertically and longitudinally relative to said transverse member, a treadle, a link extending upwardly from said treadle and having adjustable connections therewith, and flexible operative connection between the upper end of said link and the rear end of said lever.

4. In a cloth clamping device, the combination of a table, rods mounted for vertical movement in said table, a clamping bar detachably secured to the upper ends of said rods, a transverse member adjustably carried by the lower ends of said rods, springs connected to said transverse member and adapted to move said clamping bar downwardly against the table, a plurality of upwardly presented members adjustably seated at spaced intervals in said transverse member, links pivotally connected to said upwardly presented members, bearings depending from the underside of said table, levers pivotally mounted in said bearings and having their front ends pivotally connected to said links, a link operatively connected at its upper end to said levers, a treadle having a plurality of downwardly presented seats, and an operative connection between said treadle and said link, said connection being adapted to be displaceably seated in any one of the seats of said treadle.

In testimony whereof I hereunto affix my signature this 12th day of July, 1921.

BARNETT RUBINSTEIN.
